UNITED STATES PATENT OFFICE

FRIEDRICH WILHELM WEHMANN AND ERNST RUBEN DAHLSTRÖM, OF STOCKHOLM,
SWEDEN, ASSIGNEES TO AKTIEBOLAGET FORMATOR, OF STOCKHOLM, SWEDEN, A
CORPORATION

MACHINE FOR STRIPPING TOBACCO LEAVES

Application filed September 13, 1926, Serial No. 135,237, and in Sweden March 11, 1926.

The present invention refers to tobacco stripping machines of the type having a gripper or the like adapted to seize the stem preferably at some distance from the point of 5 the leaf, and further having a device for gripping the leaf, the arrangement being such, that the stem is pulled or turned out from the leaf practically in the same manner as when stripping by hand.

10 The object of the invention is to provide means whereby a more effective and good stripping is obtained than by machines of said type hitherto known.

The invention is illustrated in the accompanying drawings. Fig. 1 shows the entire machine as viewed from the side. Fig. 2 shows the machine as viewed from above. Fig. 3 shows a leaf which has been entirely stripped by cutting off the stem, and Fig. 4 shows the same leaf in a half-striped condition upon tearing. Figs. 5 and 6 illustrate certain parts of the machine as viewed from the side and partly in section. Fig. 7 discloses the pincers and adjacent parts in a 25 front view and partly in section, the machine being in its starting position, in which the pincers are open. Fig. 8 shows a tobacco leaf threaded over the pincers, the shanks of which have penetrated through the leaf so 30 as to be situated each on one side of the stem. Fig. 9 shows the pincers and adjacent parts in a front view, the pincers being closed and the other parts assuming corresponding positions. Fig. 10 shows the tobacco leaf after 35 the pincers have been closed and after a knife connected to the one shank of the pincers has cut off the stem.

1 and 2 designates two shanks, one of which 1 is rigidly connected with the holder 3 of 40 the pincers, while the other 2 is swingable about a shaft 4 attached to the holder 3. The pincers will open (Figs. 7-8) when the arm 5, which is rigidly connected with the shank 2, is brought into engagement with the catch 6 on return of the pincers into the starting 45 position, said catch 6 extending from the one arm of a lever pivotally attached to the rigid support 7, the other arm 8 of the said lever being pivotally connected with the pulling rod 9. The pincers will close (Figs. 9 and

10) when the catch 6 is moved from the arm 5 through the actuation of a treadle 60, Fig. 1, which is connected with the pulling rod 9, the closing force being then produced by a spring 10.

55 The tobacco leaf 11 is moved down over the pincers, when the latter occupy the position shown in Figs. 2, 5 and 7, that is to say when they project through a recess in the table 13 and the shanks of the pincers are 60 separated. The machine is then at rest. Immediately after the leaf has been positioned the same then resting on the table and extending with its fore-part over a part of the endless belt line 16, which according to the 65 shown embodiment consists of four belts arranged in flush and parallel with each other, the machine is started by actuation of the treadle 60, whereby the main shaft 17 and the parts mounted thereon are caused to rotate by a coupling in known manner, while the knife 14 attached to the shank 1 is caused to cut off the stem 15 at a point situated at a suitable distance from the point of the leaf. The belts 16 extending about a drum 18 attached to the shaft 17, for which belts there 70 is provided a pulley 19 near the pincers, will then move in the direction of the arrow 20 (Fig. 1) from the pincers toward the drum 18. In addition to the belt line formed by 75 the belts 16, there is another endless belt line 21 which is extended about the rolls 22 and 23 and the lower part of which serves as a carrying member for the tobacco leaf. The roll 22 is journalled in two arms 24 fast on 80 the shaft 25 of the other roll 23. Moreover, there is attached to the latter shaft an arm 26 cooperating with a cam disk 27 secured to the shaft 17, so that the roll and the belt line 21 will be alternately moved up and 85 down. The belt line 21 receives its motion about the pulleys provided therefor by the roll 23 (and, in a lowered position, also the belt line 21) bearing on the belt line 16 and the break roll 28, which is adjustably mounted 90 so that it may be tightened up against the roll 23, more or less, as desired.

The pincers are kept vertically while being in the upper position (Fig. 5). This is effected by the following means.

55

60

100

The holder 3 of the pincers forms, together with the shaft 29 and the arms 30, 31, a rigid system pivoted on the pins 32 which are mounted in the arm 33 pivotally attached to the frame, so that the center of rotation of the system coincides or approximately coincides with that point 63 of the pincers at which the leaf has been threaded over the same, whereby, on the pincers being turned 5 or rotated about the pins 32, a pulling action on the stem will not interfere with the leaf. The pincers occupy the vertical position illustrated in Fig. 5 by a roll 59 attached to the shaft 29 bearing against the lever 34 under the influence of a spring 36 inserted between the link 30 and the one arm 33. When by the actuation of the treadle 60 and the pulling rod 9 the lever 34 is moved laterally so that the pincers are caused to close, as will 10 appear from Fig. 9, the roll 59 also is disengaged from the lever 34, the pincers being then turned by the spring 36 into the position shown in Fig. 6. Then those parts of the shanks 1 and 2 of the pincers that previously 15 projected above the table 13 will be situated entirely beneath the plane of the table, so that the tobacco leaf may be pulled forth over the table without impediment. The pincers also will be inclined with respect to the leaf 20 during the stripping operation in such a manner that the stem is not bent so sharply at its point of attachment as to cause any risk for breakage at said point (see Fig. 1). The tobacco leaf 11 is still at rest, but the 25 roll 22 is now moved down from the raised position into the position shown with chain-dotted lines in Fig. 6, in which position the roll bears against the belt 16, the fore part (point) of the tobacco leaf being then caught 30 by the belt lines 21 and 16, so that the leaf is caused to move toward the drum 18 and the stripping operation commences. The pincers are still at rest in the position shown 35 in Fig. 6, until the point of the leaf at which the stem begins to leave the same has reached 40 the roll 19. At this moment, the pincers begin to move downwards in a circular path about the pivot of the arms 33, and this movement is so adapted in relation to the 45 feeding of the leaf into the machine that the point at which the stem leaves the leaf during the stripping is always at rest against the roll 19. The inclination at which the pincers are set to the arms 99 in Fig. 6 is 50 retained until the pincers have been moved down into their lowermost position by the arms 33 and the stem has been entirely detached from the leaf. When the pincers 55 turn about the pivots 32 in the manner above described, the roll 59 is brought to the outside, i. e. to the left of the arm 34 (Fig. 6). When the roll 59 again moves upwards, together with the pincers, it is to assume a position on the inside, i. e. to the right of the 60 arm 34. Therefore, the lower portion 35 of

the arm 34 is rotatable and actuated by a spring 62 in such a manner that the portion 35 forms a switch tongue on the upward movement of the roll 59, said switch tongue guiding the roll upwards on the inside of the 70 arm 34 while turning away under the action of the roll 59 when the latter moves downwards on the outside of the arm 34 in the manner hereinbefore described.

Combined with the stripping means is a 75 means adapted to remove from the detached stem such wing portions of the leaf that may have been entrained with the stem. The latter means comprises two arms 64 pivotally connected with the frame by the studs 65, 80 Fig. 2. The ends of the arms 64 adjacent the pincers are provided with opposed brushes 66, scrapers or the like, Figs. 7 and 9, and with two outwardly bent guides 67. When the pincers in moving upwards reach 85 the brushes, which under the action of the spring 68 bear against one another, the arms 69 provided on the shaft 29 will penetrate between the guides 67 so that the brushes are separated and provide a space for the 90 pincers. When by actuation of the treadle 60 the pincers are turned into the position shown in Fig. 6, the arms 69 are withdrawn from the guides 67 so that the brushes are 95 caused to close upon each other. The brushes project so far that, when the pincers move downwards in their inclined position, the shanks thereof will have to pass between the brushes, the stem carried with the pincers being then also introduced between the 100 brushes so as to pass the latter along the whole of its length, whereby all rests of the wing portion of the leaf are detached from the stem. When the pincers approach the lower extreme position, a roll 37 on a lever 105 38 extending from the axis of rotation 4 of the pivotal shank of the pincers is moved against a rigid bar 39, with the effect, that the pincers are caused to open so as to release the stem.

When the pincers move upwards, the roll 59 is brought into contact with the lower side of the arm 35 and will follow the latter and the arm 34, so that the pincers are moved into the starting position represented in Figs. 115 5, 7. The movement up and down of the pincers is brought about by the arms 33 being connected, through a link 41, with an arm 42 provided with a roll 43 which bears against a cam disk 44 secured on the main shaft. A 120 brush device for the cleaning of the pincers is represented in Fig. 1. The brush or scrapper 70 is attached to the arm 71 and receives its motion through the link 72 and the arm 73, the roll 74 of which bears against the 125 cam disk 75 on the main shaft. When the pincers are open in their lower position, the brush 70 or its equivalent is caused to penetrate between the shanks of the pincers so as to brush off all rests of the leaf from 130

the same, and also prevents the stem, in case the latter has remained sticking to the pincers on the introduction of the leaf, from being carried upwards by the pincers. The tobacco leaf lying between the belts 16 and the roll 18 is carried with the latter, so as to be situated with its front portion approximately at 40 when the machine has completed a revolution and is automatically stopped.

10 Prior to the stopping of the machine the roll 22 and the belt 21 have been automatically raised under the influence of the cam disk 27 into the position indicated with chain-dotted lines in Fig. 1.

15 When the treadle is actuated anew, that is to say, when the machine is again started and the next cycle of operations is begun, the pincers are first closed so that the stem of another tobacco leaf placed in position will be cut off. The tobacco leaf 11 then continues to move with its point downwards along the left side of the drum 18 (Fig. 1), and is brought into contact with the new leaf approximately at 45, said new leaf being now 20 stripped. The new leaf is then brought direct on top of the first leaf, in such a position relatively to the latter, that the points at which the stripping commences are caused to coincide. In this way the leaves are brought 25 into the machine, one after the other, and are caused to lie upon one another similarly to the leaves of a book, between the belt line 16 and the drum, as is shown at 46 in Fig. 1.

30 In order to prevent the stripped leaves from turning and following the belt line 21 back about the roll 23, instead of passing down under the drum 18, there is provided a brush or scraper 80 adjacent to the said roll 23, the said brush being rotatable in a counterclockwise direction according to Fig. 1.

35 The belt line 16 run, if allowed from the upper side of the break roll 19 in the direction of the arrow 20 (Fig. 1), first between the rolls 23, 28, then about the circumference of the drum 18, and finally, at the point 47, run underneath the roll 48 bearing against the front side (the left side, Fig. 1) of the drum, from which roll 48 the belts further run in an upward direction and over the rolls 49 and 50 above the drum, further downwards on the right hand side (Fig. 1) of the tension roll 51, and finally under the roll 52 situated beneath the drum, and back to the roll 19, around the left hand side of 40 which (Fig. 1) they are extended. The rolls 19, 23, 28, 49, 50 are mounted on shafts, the two ends of which are each attached to one of the two lateral frame members 53 of the machine. The roll 48, on the other hand, 45 is mounted on the free outer ends of two arms 54 extending from bosses rotatable about the shaft of the roll 49, said arms 54 being thus adapted to be swung in a vertical direction together with the roll 48. The shaft of the tension roll 51, which latter

serves to keep the belt under tension to such an extent that space is provided between the belt and the drum for a suitable number of leaves, is attached to two arms 55 rigidly connected with a shaft 56 which is rotatably journalled in the frame members 53. An arm 57, which is under the influence of a spring 58 secured to the frame by means of a pin 61, is also fast on the said shaft 56.

70 When a suitable number of leaves have been collected (booked) between the belts 16 and the drum, they are brought forth in such a manner that the levers 54 are raised by hand, together with the roll 48, from their lower position to the position indicated with chain-dotted lines (Fig. 1), so that the bunch of leaves may be caught with the hand when moving past the opening provided through said raising of the levers 54.

75 This method for collecting (booking) and for removing the leaves out of the machine respectively is known per se, as is also the arrangement of one or more tension rolls for the belts 16.

80 The belt line 16 can, of course, instead of four belts, consist of a greater or lesser number (only one, if desired) of belts, for instance, two belts acting each on one side of the stem of the leaves.

85 The invention may of course be carried into effect in many ways other than those illustrated and described, without the principle of the invention being departed from. For instance, the leaf may be positioned on the table while the pincers are in their lower position, 90 so that the pincers (when turned up) penetrate through the leaf from below, while in an open position with the shanks on both sides of the stem.

95 What we claim as new and desire to secure 100 by Letters Patent of the United States of America is:—

1. In a device for stripping the stem from a tobacco leaf, the combination of a gripper adapted to seize the stem at some distance 110 from the tip end of the leaf, a second means for gripping the leaf and moving it through the machine, said means consisting of two belts arranged to grip the leaf therebetween, front pulleys for said belts, said first named 115 gripper in its leaf engaging position being located at a small distance in front of said pulleys, a member on which the gripper is mounted and adapted to move in such a way in relation to the feeding movement of the 120 said belts that the stemming will occur at the front side of one of the pulleys.

2. In a device for stripping the stem from a tobacco leaf, the combination of a gripper adapted to seize the stem at some distance 125 from the tip end of the leaf, two belts for feeding the leaf into the machine, front pulleys for said belts, said gripper in its leaf engaging position being located at a small distance in front of said pulleys, said pulleys 130

being movable to and from each other and adapted when brought towards each other to cause the said belts to grip therebetween the point end of the leaf, and to move the leaf in the feeding movement of the belts.

5 3. In a device for stripping the stem from a tobacco leaf, the combination of a gripper adapted to seize the stem at some distance from the tip end of the leaf, two belts for feeding the leaf into the machine, front pulleys for said belts, said gripper in its leaf engaging position being located at a small distance in front of said pulleys, said pulleys being movable to and from each other and 10 adapted when brought towards each other to cause the said belts to grip between themselves the tip end of the leaf, and to move the leaf in the feeding movement of the belts, the said belts being arranged one above the other, 15 the lower one of them being stationary and being adapted to serve as a support for the tip of the leaf, and the upper one of said belts being swingable to and from the lower one.

20 4. In a device for stripping the stem from a tobacco leaf, the combination of a gripper adapted to seize the stem at some distance from the tip end of the leaf, means for gripping the leaf and feeding it into the machine, 25 said means consisting of two belts which are arranged to grip the leaf therebetween, front pulleys for said belts, said gripper in its leaf engaging position being located at a small distance in front of said pulleys, the gripper being mounted on a member, which is adapted to move in such a way in relation to the feeding movement of the said belts that the stemming will occur at the front side of one of the pulleys, the said belts being arranged one 30 above the other, the lower one of them being stationary and being adapted to serve as a support for the tip of the leaf, when this latter is placed in the machine, and the upper one of said belts being swingable to and from the lower one.

35 5. In a device for stripping the stem from a tobacco leaf, the combination of a gripper adapted to seize the stem at some distance from the tip end of the leaf, and located in front of a device for feeding the leaf rearwardly when the stem has been seized by the gripper, said feeding device consisting of two leaf feeding belts arranged one above the other, the lower one of said belts being adapted to support the point of the leaf, a fixed leaf support arranged immediately in front of said lower belt and lying in flush therewith, the upper one of said belts being adapted to 40 swing about its rear end from a position apart from the lower belt to a position close thereto whereby the said two belts grip the leaf lying on the lower belt and move the leaf rearwardly.

65 6. In a machine for stripping the stem from a tobacco leaf the combination of a de-

vice for gripping the leaf and moving it into the machine, a gripper adapted to seize the stem of the leaf, means whereby the said device and said gripper are moved in relation to each other to cause the stem to be pulled from the leaf, and a stem cleaning device adapted to engage the stem and remove the remaining tobacco from the stem immediately after the stripping operation, and which in its operative position is located in the path of movement of the gripper, means for holding said cleaning device in an inoperative position to permit the gripper to pass it and to perform its stripping movement, and means whereby the cleaning device is brought in its operative position so as to remove the remaining tobacco from the stem.

70 In testimony whereof we affix our signatures.

FRIEDRICH WILHELM WEHMANN.

ERNEST RUBEN DAHLSTRÖM.
